US00D890723S

(12) **United States Design Patent** (10) **Patent No.:** **US D890,723 S**
(45) **Date of Patent:** **** Jul. 21, 2020**

(54) **ELECTRONIC HOUSING**

(71) Applicant: **Peripherii Inc.**, Chappaqua, NY (US)

(72) Inventors: **Priti Moudgill**, Chappaqua, NY (US);
Sonal Budhiraja, Palo Alto, CA (US)

(73) Assignee: **Peripherii Inc.**, Chappaqua, NY (US)

(**) Term: **15 Years**

(21) Appl. No.: **29/717,270**

(22) Filed: **Dec. 16, 2019**

Related U.S. Application Data

(63) Continuation-in-part of application No. 15/751,356, filed as application No. PCT/US2016/052401 on Sep. 18, 2016.

(51) **LOC (12) Cl.** **14-01**

(52) **U.S. Cl.**

USPC **D14/223; D14/206**

(58) **Field of Classification Search**

(57) **CLAIM**

The ornamental design for an electronic housing, as shown and described.

DESCRIPTION

This application is additionally related to but does claim priority from U.S. patent application Ser. No. 29/633,217 filed Jan. 12, 2018 now issued as U.S. Pat. No. D. 815,619.

FIG. 1 is a front top perspective view of the invention.

FIG. 2 is a rear bottom perspective view thereof.

FIG. 3 is a bottom plan view thereof.

FIG. 4 is a top plan view thereof.

FIG. 5 is a left side elevation view thereof.

FIG. 6 is a right side elevation view thereof.

FIG. 7 is a front elevation view thereof.

FIG. 8 is a rear elevation view thereof.

FIG. 9 is a front top perspective view of a further embodiment of the invention.

FIG. 10 is a rear bottom perspective view thereof.

FIG. 11 is a bottom plan view thereof.

FIG. 12 is a top plan view thereof.

FIG. 13 is a left side elevation view thereof.

FIG. 14 is a right side elevation view thereof.

FIG. 15 is a front elevation view thereof; and,

FIG. 16 is a rear elevation view thereof.

In the drawing the claimed design is defined by the shaded surfaces; the broken lines depict unclaimed environment that forms no part of the claimed design.

1 Claim, 7 Drawing Sheets
